ANTIGLARE ILLUMINATION APPARATUS

Antonio de Aranzadi e Irujo, Pamplona, Spain

Application August 18, 1934, Serial No. 740,520
In Spain August 24, 1933

3 Claims. (Cl. 240—8.2)

This invention is directed to apparatus for illuminating the road during passing of approaching cars. It consists of means for illuminating the road in such a way as to enable drivers to pass safely and have a clear view of the road behind the other car, until their own head lights are switched on fully.

It is generally accepted as a rule of the road that upon approaching a vehicle traveling in the opposite direction, the powerful headlights which produce a glare in the eyes of the on-coming driver are turned off and replaced by regulation passing lights. This operation is usually effected when the approaching vehicles are about 350 yards or more apart. The regulation passing lights allow the two vehicles to advance safely until they are about 100 yards apart. At this point each car is about to enter the dark zone on the left side of the other. The period in which the cars approach from a point of about 350 yards apart to a point of about 100 yards apart can be considered to be the first phase of the passing.

The second phase begins when the cars are about 100 yards apart and terminates when the cars are along-side each other and the bright head lights are again turned on. This second phase is the shortest but most dangerous, as the dazzling of the regulation passing lights compels the drivers to go on blind without noticing obstacles which could appear during the passing or immediately thereafter.

An object of this invention is to furnish the cars with a light system complementary to the regulation lights for passing, that will illuminate the side of each car (each car illuminates the portion of the road where the other has to go) during the second phase of the passing, with a very intense and diffused light avoiding as far as possible dark patches in the illuminated zone. This light is directed almost parallel to the axis of the road and in such a way as not to dazzle either the coming or the following car.

The present invention will be more easily understood by following the accompanying drawing.

Figure 1 is a vertical section through the anti-glare apparatus and its holder, according to the invention.

Fig. 2 is a perspective view illustrating the disposition of the spherical mirror in relation to the half disk.

Fig. 3 is a perspective view of the shield and the channel clamping ring.

Fig. 4 is a perspective view of an apparatus

similar to Fig. 1, but without the spherical mirror and shield.

Fig. 5 shows a plan view of a car furnished with the new lamps.

The anti-glare apparatus has a special bulb (A) of higher power which operates at a very high temperature. The car's usual battery is strong enough for these lamps as their use is limited to a few seconds.

Great illuminating intensity is necessary for the satisfactory result of this invention and taking advantage of the short duration of the second phase of the crossing, I can strengthen the intensity of the bulbs, increasing their current consumption and working temperature, to limits not reached as yet in automotive construction.

The apparatus has a parabolic reflector, B which carries the lamp socket, C with its spring contact, D. All these interior elements are protected by a casing, E.

A cap-shaped spherical mirror F is provided to direct the light towards the upper part of the reflector, so that the light rays projected by the lower portion of the bulb are usefully employed. It is supported by a disk G, the upper portion of which is removed for the passage of light and the lower portion of which prevents the light from passing through the lower portion of the front of the apparatus.

The disk G is encircled by a flange T affixed in the rim of reflector B. Flange T forms a circular cavity carrying a gasket H for supporting the lens I. This lens is fluted vertically in order to broaden the light beam.

J is a gasket which closes the small space between the lens I and the casing E, making the inner part of the apparatus dust- and watertight. Gasket J, moreover, provides an elastic packing between the clamping ring K and the lens. When screw U is tight, ring K retains the lens I and the reflector B against the casing E.

The visor-like shield L, which is carried by ring K, prevents the driver of the on-coming car from being dazzled. The height and direction of the apparatus can be adjusted. The lower part of the shield lies in a horizontal plane passing through the axis of the apparatus. Its length is calculated to let out most of the light, which is directed obliquely downwardly onto the road. Moreover, it serves as a reflector directing the horizontal and upwardly directed beams downwardly. The road is thus illuminated from the lower part of the apparatus.

M is a cable or conductor which connects the

contact D of the lamp socket with the connector N which, in turn, is connected to a battery.

The casing E is surrounded by a supporting member O clamped in position by screw V. At 5 the lower portion of the member O there is provided a threaded stud R which is adapted to be received in openings in the arms of a clamping bracket Q which is adjustably secured to rod P by nuts S. Rod P is carried by a bracket 10 which may be mounted at any point on the car by means of nut W. This construction permits the mounting of the apparatus without the use of special brackets.

Fig. 5 shows how the apparatus are to be fixed 15 to a car in order to obtain the best results. (X) and (Z) are the anti-glare apparatus of Fig. 1 and (Y) the lamp of Fig. 4. The apparatus (Z) is fastened to a transverse bar in front of the radiator or any similar position. It operates 20 during the second phase of the passing instead of the regular lights illuminating the road ahead of the car without disturbing the coming driver nor harming the effect of the side lights.

Lamp (Y) is fixed on the edge of the lower 25 and back part of the left front fender. It illuminates the road backwards in a direction parallel to its axis but without disturbing the driver of the following car as long as the latter keeps to his side of the road (the first car acting as a shield).

The anti-dazzle apparatus (X) is fixed on the left rear fender, directed forwards and also parallel to the road. It illuminates a much shorter zone than lamp (Y). This lamp, together with 35 (Z), helps the driver of the car equipped with the same.

The anti-glare apparatus of Fig. 1 can be changed into the projector of Fig. 4 by substituting the pieces shown in Fig. 2, by a ring 40 with a flange (T) and pieces shown in Fig. 3, and by a clamping ring (K). By this simple change of two pieces, I obtain the two different types of apparatus required for my system, even though the same have rather different functions. 45 This represents an appreciable economic advantage, as it makes possible standard manufacture.

On rainy days and especially on bituminous roads, the light of the lamps X and Z might 50 possibly be reflected by the road acting as a mirror. They ought to be switched off, leaving Y illuminating backwards.

These lamps are switched either by hand or foot and in different ways which are immaterial to the principle of the invention.

I claim as my invention:

1. An anti-glare projecting lamp, comprising a casing, a parabolic reflector mounted therein, a bulb supported by said reflector, said casing and reflector having nesting forwardly extending flanges, an annular member concentrically mounted in the flange of the reflector, a semi-circular disk carried by the lower half of said annular member, reflecting means carried by said disk for projecting light falling thereon upwardly and rearwardly to the upper portion of said parabolic reflector, a visor projecting forwardly from the front of said lamp and extending downwardly to the axis of said parabolic reflector, said annular member being provided with an annular recess, a lens gasket in said recess, a lens positioned against said gasket, and clamping means extending circumferentially about said casing for retaining said lens, annular member and reflector in assembled position. 10

2. An anti-glare projecting lamp according to claim 1, in which said reflecting means comprises a cap-shaped spherical mirror having a straight upper edge substantially in alignment with the lower horizontal edge of the visor. 15

3. In an illuminating system for automotive vehicles, comprising in combination with an automotive vehicle a projecting lamp mounted at the rear lower portion of the left front fender in a position to project light rearwardly parallel to the road, and an anti-glare projecting lamp mounted on the rear portion of the left side of the car and positioned to direct light forwardly parallel to the road, said anti-glare device comprising a casing, a parabolic reflector mounted therein, a bulb supported by said reflector, said casing and reflector having nesting forwardly extending flanges, an annular member concentrically mounted in the flange of the reflector, a semi-circular disk carried by the lower half of 30 said annular member, reflecting means carried by said disk for projecting light falling thereon upwardly and rearwardly to the upper portion of said parabolic reflector, a visor projecting forwardly from the front of said lamp and extending downwardly to the axis of said parabolic reflector, said annular member being provided with an annular recess, a lens gasket in said recess, a lens positioned against said gasket, and clamping means extending circumferentially 35 about said casing for retaining said lens, annular member and reflector in assembled position. 40
